UNITED STATES PATENT OFFICE.

CHARLES FRANKLIN HUNEYCUTT, OF CHARLOTTE, NORTH CAROLINA, ASSIGNOR OF
ONE-HALF TO C. F. BRETHOLL, OF CHARLOTTE, NORTH CAROLINA.

SHEET-GUIDE FOR PRINTING-PRESSES.

1,342,113.

Specification of Letters Patent. Patented June 1, 1920.

Application filed September 10, 1919. Serial No. 322,912.

To all whom it may concern:

Be it known that I, CHARLES FRANKLIN HUNEYCUTT, a citizen of the United States, and a resident of Charlotte, in the county of 5 Mecklenburg and State of North Carolina, have invented certain new and useful Improvements in Sheet-Guides for Printing-Presses, of which the following is a specification.

10 My invention relates to sheet guides for printing presses and more particularly to movable sheet guides adapted to engage and properly position the sheets for impression.

An important object of my invention is to 15 provide a movable sheet guide particularly adapted for use with bed-and-platen presses of the Gordon type in which the guides will engage with the sheets as they are fed to the platen, influence them to proper positions 20 for impression and leave the impression surface of the platen immediately prior to the act of impression with the sheets maintained in proper position by the gages ordinarily provided.

25 Another object is to provide means for insuring correct delivery of the sheets to the platen when automatic press feed devices of the endless tape type are employed.

Other objects and advantages reside in 30 certain novel features of the construction, arrangement and combination of parts and will become apparent as the description proceeds, reference being had to the accompanying drawings forming part of this specification and in which:—

35 Figure 1 is a side elevation of my improvement showing the parts disposed in normal position,

Fig. 2 is a side elevation showing the parts 40 in the position they take when the platen is in position for impression,

Fig. 3 is a detail perspective view showing the guide fingers and associated supporting and operating structure,

45 Fig. 4 is a side elevational view of my improvement associated with an automatic press feed device of the endless tape type,

Fig. 5 is a plan view showing my improved guiding means associated with the 50 feed device,

Fig. 6 is a detail perspective view of the guiding strip and supporting structure of the guiding means to the feed device.

Heretofore in the printing art, and especially since the advent of automatic press

feeding devices, considerable and serious difficulty has been experienced in properly positioning the sheet on the platen for impression. This has been occasioned by a variety of causes but mostly because of the 60 tendency of the sheet to curl or because of the sheet going past the gages provided to maintain the same in proper position. In most instances there results a clogging of the machine, necessitating a press stop, but in 65 all instances there is a loss of material and of time. My invention aims to eliminate these disadvantages by providing movable sheet guides which engage the sheets as they are delivered to the platen, overcome any 70 tendency of the sheet to curl, and influences the sheets to proper position for impression. Immediately prior to impression the guides are automatically withdrawn from the impression surface, the sheets being then maintained in proper position by the gages ordinarily provided. In this manner, not only 75 are the disadvantages above enumerated overcome, but in addition, forms with a very close margin may be run on presses employing automatic press feeders, an operation not possible with the devices hitherto employed, in which the sheet guides provided do not leave the impression surface.

80 Referring to the drawings, it will be seen 85 my invention is shown applied to a bed-and-platen press of the Gordon type and includes a frame A and an oscillating platen B mounted on said frame. The platen is provided with the usual feed gages C and grippers D for maintaining the sheet in position 90 on the platen. The usual type bed E and inking plate and rollers F and G respectively, are provided as shown diagrammatically in Fig. 4.

95 A bracket 10 is secured to the under side of the platen at the lower end thereof by suitable fastening means engaged with the platen and with the aperture 11 and slot 12 in the bracket. The body of the bracket is offset as shown in Fig. 3 and bracket extensions 13 are secured to the body of the bracket and have their outer ends provided with suitable journals for the oscillating shaft 14. Collars 15 are secured to the shaft 100 adjacent the outer side of each of the bracket extensions and serve to prevent displacement of the shaft from the journals of the bracket extensions. The shaft is provided with a crank 16 at one end thereof. 110

Projecting radially from the collars 15 are pins 17 and coöperating with the pins 17 and hooks 18 secured to the body portion of the bracket are retractile springs 19 which 5 serve to maintain and return the oscillating shaft 14 in normal or central position.

Secured to the oscillating shaft 14 and constrained to oscillate therewith, are 10 holders 20. These holders are in the form of metallic strips having one end bent around the oscillating shaft and fastened thereto by screws 21 and having their other end bent upon itself and adapted to be drawn tight against the body of the strip 15 by screws 22. The bight of this bend is provided with a slot which receives the inner end of the guiding means 23 in the form of thin strips of flexible material having their outer ends bent back upon the strip to form 20 hooked ends 23'. These strips constitute guiding fingers and are adapted to be adjustably secured to the holders 20. The strips extend upwardly through the usual feed gages and in their normal position, as 25 shown in Figs. 1 and 4, extend over and above the surface of the platen for a relatively great distance. In the printing position of the platen as shown in Fig. 2, these guiding fingers are withdrawn from the 30 surface of the platen, the hooked ends thereof being engaged with the feed gages, as shown in Fig. 2.

Secured to the frame of the press is a 35 projection in the form of a curved piece of resilient metal 24. On the downward movement of the platen the crank 16 engages with the projection and rotates the shaft 14 to move the guide fingers from the position shown in Figs. 1 and 4 to the position shown 40 in Fig. 2. On the return movement of the platen the crank is released from engagement with the projection and the retractile springs 19 reversely rotate the shaft 14, completing the oscillating movement of the 45 shaft and returning the guide fingers to the position shown in Figs. 1 and 4.

When an automatic press feed device of the endless tape type is employed, as shown 50 diagrammatically in Figs. 4 and 5, as including endless tapes H and driving rollers I, I provide additional guiding means to insure delivery of the sheets to the platen in correct position. This guiding means consists of a suitable support preferably in 55 the form of a tubular housing 25 secured to a bracket 26. Slidable in this housing is a bar 27 having a vertically depending portion 28 to which is secured an elongated guide strip 29 having an adjustable sheet 60 bearing portion 30 fixed thereto. This adjustable sheet bearing portion is controlled in position by a set screw 31 and the bar 27 is controlled in position by a set screw 32 extending through the suitable housing and 65 bearing against the bar. The bars 27 are

adjusted in the housing as required by the sheet and the sheet bearing portions are adjusted to position to press the sheets against the endless tape and in this manner correct delivery of the sheets to the platen is insured. 70

In practice, it is to be noted that the guide fingers engage the sheets as they are delivered to the platen by virtue of the fact that they extend for a relatively great distance over and above the platen and have therefore, guiding surfaces having a relatively great range of action. In this manner, irrespective of whether the sheets are delivered closely adjacent the surface of the 75 platen, or are delivered to the platen at some distance from the surface thereof, they are engaged by the guiding surfaces of the guiding fingers and the downward movement of the guiding fingers, due to the movement of the platen and the engagement of the crank with the projection on the frame, simultaneously influences or draws the sheet to the surface of the platen and to proper position on the platen for impression, leaving the sheets maintained in this proper position by the action of the gages and grippers ordinarily provided. After the positioning of the sheet, however, the movement of the guiding fingers is continued until they are 80 entirely withdrawn from the impression surface of the platen as shown in Fig. 2. It is 85 entirely withdrawn from the impression surface of the platen as shown in Fig. 2. It is to be noted that the guiding fingers not only 90 properly position the sheet, but by virtue of their longitudinal movement over the sheet, serve to straighten the same out and thereby overcome any tendency to curl. The feature of the adjustment of the fingers 95 of the holders and the flexible quality of the material constituting the fingers, insures correct and easy adaptation to all the conditions and requirements of their uses. 100

I claim:—

1. A sheet guide for printing presses, including a frame and oscillating platen on 110 said frame, consisting of a bracket secured to the underside of said platen and having extensions provided with bearings, an oscillating shaft having a crank on one end thereof mounted in said bearing, holders 115 fixed to said shaft, movable guide fingers secured in said holders and extending over the platen and adapted to engage the sheets to simultaneously influence them to the surface of the platen and to draw them to 120 proper position for impression, a projection secured to said frame and adapted to be engaged with the crank on the downward movement of said platen to move said guide fingers and to withdraw them from the 125 impression surface of said platen, and retractile springs to reversely rotate said shaft and return said guide fingers to initial position on the upward movement of said platen. 130

2. A sheet guide for printing presses, in-

- cluding a frame and an oscillating platen on said frame, consisting of a bracket secured to the under side of said platen and having extensions provided with bearings, 5 an oscillating shaft having a crank on one end thereof mounted in said bearing, holders fixed to said shaft, movable guide fingers secured in said holders and extending over the platen and adapted to engage the sheets 10 to simultaneously influence them to the surface of the platen and to draw them to proper position for impression, and a projection secured to said frame and adapted to be engaged with the crank on the downward movement of said platen to move said guide fingers and to withdraw them from the impression surface of said platen.
3. A sheet guide for printing presses, including a frame and an oscillating platen 20 on said frame, consisting of a bracket secured to said platen, a shaft journaled in said bracket, holders fixed to said shaft, guide fingers adjustably secured in said holders having a guiding surface extending over the platen in the direction of feed of the sheet to engage the sheets before they are delivered to the platen, means operative by the movement of said platen to oscillate said shaft to move said guide fingers and to withdraw them from the impression surface of the platen prior to the act of impression and to return them to initial position subsequent to the act of depression, and means for constraining said guiding fingers to 30 guiding motion across and toward the platen in the direction of the feed of the sheet, whereby the guiding surface of said fingers simultaneously move the sheets toward the surface of the platen and draw them to proper position for impression.
4. A sheet guide for printing presses, including a frame, an oscillating platen on said frame, consisting of bearings secured to said platen, a shaft mounted in said bearings, guide fingers operated by said shaft and having a guiding surface extending over the platen in the direction of feed of the sheet to engage the sheets before they are delivered to the platen, means to rotate said shaft to actuate said guide fingers and to withdraw them from the impression surface of the platen on the downward movement thereof, means to reversely rotate said shaft and return the guide fingers to initial position on the upward movement of said platen, and means to constrain said guide fingers to guiding motion across and toward the platen in the direction of the feed of the sheet, whereby the guiding surfaces of 50 said fingers simultaneously move the sheets toward the surface of the platen and draw them to proper position for impression.
5. A sheet guide for printing presses comprising guiding means having a guiding surface extending over the platen of the 65
- press in the direction of feed of the sheet to engage the sheets before they are delivered to the platen, means for moving said guiding means and withdrawing the guide means from the impression surface of the platen 70 operated by and in synchronism with the movement of the platen, and means for constraining said guiding means to guiding motion across and toward the platen in the direction of the feed of the sheet whereby 75 the guiding surface of said guiding means simultaneously moves the sheets toward the surface of the platen and draws them to proper position for impression.
6. A sheet guide for printing presses, comprising guiding means having a guiding surface extending over the platen in the direction of feed of the sheet to engage the sheets before they are delivered to the platen, means for moving said guiding 80 means and withdrawing them from the impression surface of the platen, and means for constraining said guiding means to guiding motion across and toward the platen in the direction of feed of the sheet whereby 85 the guiding surface of said guiding means simultaneously moves the sheets toward the surface of the platen and draws them to proper position for impression.
7. A sheet guide for printing presses comprising sheet guiding means extending from the platen of the press in the direction of feed of the sheet and having an effective guiding surface at a relatively great distance from the platen to engage the sheets 90 before they are delivered to the surface of the platen, means for moving said sheet guiding means and for withdrawing the same from the impression surface of the platen, and means for constraining said 95 sheet guiding means to guiding motion across and toward the platen in the direction of the feed of the sheet whereby the guiding surface of said fingers simultaneously influence the sheet to the surface of the platen 100 and move them to the proper position for impression.
8. A sheet guide for printing presses comprising movable guide fingers having a guiding surface extending over the platen in the 115 direction of feed of the sheet to engage the sheets before they are delivered to the platen, means for actuating said guide fingers, and means for constraining said guiding fingers to a relatively large horizontal 120 and a relatively small downward motion with respect to the platen in the direction of the feed of the sheet whereby the guiding surface of said fingers engage the sheets before they are delivered to the surface of the 125 platen and simultaneously influence the sheets toward the surface of the platen and move them to proper position for impression.
9. A sheet guide for printing presses com-

prising flexible guide fingers having a guiding surface extending over the platen in the direction of the feed of the sheet adapted to engage sheets before they are delivered to the platen, means for actuating said guide fingers, and means constraining said guide fingers to guiding motion, across and toward the platen in the direction of feed of the sheet whereby the guiding surfaces of said fingers simultaneously influence the sheets toward the surface of the platen and move them to proper position for impression.

10. A sheet guide for printing presses comprising upwardly curved guide fingers having a guiding surface extending over the platen in the direction of feed of the sheets, means for moving said guiding fingers and for withdrawing them from the platen of the press, and means for constraining said 15 guiding fingers to guiding motion across and toward the platen in the direction of the feed of the sheet whereby the guiding surface of said fingers simultaneously move the sheets toward the surface of the platen and 20 draws them to proper position for impression.

11. A sheet guide for printing presses comprising resiliently flexible guide fingers upwardly curved over the platen of the 25 press having a guiding surface extending over the platen in the direction of the feed of the sheet to engage the sheets before they are delivered to the platen, means for moving said guiding fingers and for withdrawing them from the platen of the press, and 30 means for constraining said guiding fingers to guiding motion across and toward the platen in the direction of the feed of the sheet whereby the guiding surface of said 35 fingers simultaneously moves the sheets toward the surfaces of the platen and draws them to proper position for impression.

12. A sheet guide for printing presses comprising resiliently flexible guide fingers 40 upwardly curved over the platen of the 45

press having a guiding surface extending over the platen in the direction of the feed of the sheet to engage the sheets before they are delivered to the platen, means for moving said guide fingers and for withdrawing them from the platen of the press, and means rigidly secured to the platen having an opening therethrough for the passage of said guide fingers to constrain said guide fingers to guiding motion across and toward the platen in the direction of the feed of the sheet whereby the guiding surfaces of said fingers simultaneously move the sheets toward the surface of the platen and draw them to proper position for impression.

13. A sheet guide for printing presses comprising guiding means having a guiding surface extending over the platen of the press in the direction of feed of the sheets to engage the sheets before they are delivered to the platen and means for moving said guiding means across and toward the surface of the platen whereby the guiding means simultaneously move the sheets toward the surface of the platen and draw them to proper position for impression.

14. A sheet guide for printing presses including a frame, a platen oscillating on said frame and sheet gages on said platen consisting of guide fingers extending through 75 said sheet gages and upwardly curved over the platen of the press and adapted to engage the sheets to simultaneously move the sheets toward the surface of the platen and draw them to proper position for impression said guide fingers having their outer ends hooked, and means for actuating the guide fingers through their guiding movements and for withdrawing them from the impression surface of the platen, the hooked 80 ends of said guide fingers being engaged with the feed gages in said withdrawn position.

CHARLES FRANKLIN HUNEYCUTT.
